UNITED STATES PATENT OFFICE.

GUSTAV RUDOLPH SCHIMMEL, OF DETROIT, MICHIGAN.

DESIGN FOR A NURSING-BOTTLE.

SPECIFICATION forming part of Design No. 22,052, dated December 6, 1892.

Application filed August 10, 1892. Serial No. 442,720. Term of patent 14 years.

To all whom it may concern:

Be it known that I, GUSTAV RUDOLPH SCHIMMEL, a citizen of the United States, residing at Detroit, in the county of Wayne and State of Michigan, have invented and produced a new and original Design for a Nursing-Bottle, of which the following is a specification, reference being had to the accompanying drawings.

10 Figure 1 is a side elevation of a nursing-bottle, showing my design. Fig. 2 is a cross-section thereof on line $x\ x$.

The leading feature of my design consists in a bottle of flask shape having a base formed

15 on its edge at an acute angle to the longitudinal axis thereof.

A is a bottle-body of substantially an oval flask shape with a neck B.

C is a base formed on the edge at an acute angle to the longitudinal axis D of the bottle. 20

What I claim as my invention is—

The design for a nursing-bottle herein described and shown.

In testimony whereof I sign this specification in the presence of two witnesses.

GUSTAV RUDOLPH SCHIMMEL.

Witnesses:

JAMES W. WHITTEMORE,
N. L. LINDOP.
